FOLDING DOOR

Robert A. Miller, Tarentum, and Carroll Howard, Rochester, Pa., assignors to Pittsburgh Plate Glass Company, a corporation of Pennsylvania

Application July 13, 1944, Serial No. 544,800

12 Claims. (Cl. 160—36)

1

This invention relates to folding door structure and it has particular relation to folding door units adapted to carry plate glass as the principal body portion of each door unit.

One object of the invention is to provide a folding door structure capable of serving as a barrier across a relatively large space and adapted to be transferred as a unit to a storage compartment when not in use.

Another object of the invention is to provide an improved folding door structure adapted to be installed in conjunction with particular structure of deck houses and other superstructure of ships.

Another object of the invention is to provide an improved door structure and hinged connections between a series of folding door units and supports for movably carrying and shifting the position of the entire door structure.

In one form of the invention a series of glass door units are supported upon overhead tracks by means of spaced trolleys. Certain of the door units are connected together adjacent their edges in hinged relation remote from the location of the trolleys and others are connected directly below the trolleys. In this arrangement the doors are hinged either to trolley extensions or to intermediate posts so arranged that each door can be swung bodily outwardly from the vertical plane of the overhead trolleys. The several door units thus connected can be moved as a unit onto an auxiliary support which is itself hinged so that the structure can be shifted into a compartment.

The upper and lower portions of the structure are guided by means of rollers travelling between track members formed by upper and lower rails. In order to traverse a relatively large space between deck house walls of a ship or between other or similar walls, two folding door structures are employed, each to be operated as a unit and extended from opposite directions so as to meet at a central location between the deck houses. The inner or adjacent units of each of these structures are independently hinged upon part of the movable structure to provide swinging double doors for passage from one side to the other of the structure.

When this type of structure is applied to a sloping deck the door hinges are so arranged that the door units, when folded, swing out over the downwardly sloping portion of the deck which will offer no interference to the operation of the doors.

In the drawings:

Fig. 1 is a fragmentary diagrammatic side elevation of folding door structures and supports 55

2

therefor; Fig. 2 is a combined diagrammatic plan and horizontal section of compartment structure and door units in folded relation; Fig. 3 is a fragmentary diagrammatic horizontal section of folding door structure taken substantially along the line III—III of Fig. 1; Fig. 4 is a horizontal section, on a larger scale, also taken substantially along the line III—III of Fig. 1, but with portions of the structure omitted; Fig. 5 is a combined fragmentary side elevation and vertical section illustrating in detail an end portion of the door structure; Fig. 6 is a fragmentary side elevation, combined with a vertical section of a central portion of the folding door structure and including a trolley assembly, all on a larger scale; Fig. 7 is a bottom plan of a portion of a lower door hinge and roller arrangement; Fig. 8 is a fragmentary vertical section, on a larger scale, taken substantially along the line VIII—VIII of Fig. 1; Fig. 9 is a cross-section of a channel guide and cover mounted in a floor or deck; Fig. 10 is a fragmentary side elevation of trolley and door structure together with a vertical section of a portion of a lower channel guide; Fig. 11 is a fragmentary side elevation of adjacent door units, together with hinging connections therefor; Fig. 12 is a bottom plan of the central portion of the structure shown in Fig. 11; Fig. 13 is a fragmentary vertical section taken substantially along the line XIII—XIII of Fig. 1; and Fig. 14 is a fragmentary vertical section taken substantially along the line XIV—XIV of Fig. 1.

In practicing the invention a pair of folding door structures 20 and 21 are carried between overhead superstructure 23 and a floor or deck 24 of a ship. The surface of the latter in certain instances may slope as indicated in Figs. 13 and 14. In this particular description the folding door structures are applied to a deck of a ship.

A relatively long metal guide 25 of channel form opening upwardly is rigidly anchored in the deck by means of fasteners 26 (Fig. 9) in such manner that it is disposed slightly below the deck surface. A cover rail or strip 29, having a hinge connection 30 along one edge by which it is connected to an adjacent edge of the channel guide, covers the latter or leaves it open depending upon the position of the folding door structures. A thicker portion or rib 31 projecting from one side of the rail is adapted to fit into the channel guide so that the rail may lie substantially flush with the surface of the deck as indicated in Fig. 9.

The ship superstructure includes deck houses 24 between which the folding door structures operate. Each of the structures includes a series

of door units 35, 36, 37, 38, and 39. Each of these units includes upper and lower metal channel frame members 40 and 41 for receiving upper and lower marginal portions of door panels 42 which can be in the form of relatively heavy tempered glass plates transparent or semi-transparent, or opaque. The upper channel frames 40 include upwardly-extending flanges 45 and downwardly-extending flanges 46 which define oppositely facing double channel structure. Likewise, the bottom channel frames 41 include upwardly and downwardly-extending flanges 48 and 49.

An overhead track 50 carried by the ship superstructure by means of suitable hangers 51 supports the folding door structures in suspended relation by means of trolleys 52, 53, and 54, which travel upon inwardly turned and spaced flanges 56 of the track. Since the trolleys are all substantially the same in structure only one of them will be described in detail.

Each trolley includes a substantially horizontal frame 60 having transverse horizontal axles 61 extending therethrough to support rotatably two pairs of wheels 62 which roll upon the track flanges 56. End portions of the frame between the wheels of the respective pairs extend downwardly to form bosses 64 having vertically tapped openings 65 in which vertical stud shafts 67 are screw-threaded to receive sleeve-like rollers 70 that are held in place by means of heads 71 on the lower ends of the shafts 67. A set-screw 72 which is screw-threaded into each boss 64 bears against the threaded stud shaft to prevent accidental displacement thereof. These rollers 70 fit between opposed edges of the track flanges 56 (Fig. 8), to assist in guiding the trolley linearly upon the tracks and to prevent the trolley from turning about a vertical axis.

A yoke 74, having an upwardly bowed bearing portion 75, extends freely between edges of the track flanges and is suspended from the central portion of each trolley frame upon a bolt 76 extending therethrough. The lower portion of the yoke includes an integral horizontal plate 78.

The inner or first trolley 52 directly suspending the door unit 35 has its yoke 74 connected to an upright post 80 (Fig. 5) in which a plug 81 is welded for the purpose of carrying an upright bolt 82 rigidly secured thereon and which rigidly secures the yoke 74 to the post 80.

An upper stud shaft 84 having a lower head 85 is rigidly mounted by screw-threading or otherwise in the yoke plate 78 of the end trolley 52, and has a bearing mounting in a block 86, the latter being rigidly secured by means of screws 89 in the frame member 40 between its flanges 45. This block is located at the upper inner corner of the door unit 35.

The lower portion of the post 80 has a metal bar 90 rigidly mounted thereon by means of suitable fasteners 91 and projects horizontally below and parallel to the plate 78. A stud shaft 92 of screw form is threaded through the bar 90 in axial vertical alignment with the upper stud shaft 84 and has an upper unthreaded bearing portion 94 which rotatably receives a lower block 95 mounted rigidly by means of screws 96 between the downwardly-extending flanges 49 of the lower channel member 41. The door unit 35 is thus hinged adjacent its rear edge upon the stud shafts 84 and 92 for pivotal movement relative to the post 80 and about a vertical axis.

The lower end of the stud shaft 92 has a roller 98 mounted thereon and is maintained against displacement therefrom by means of a lower head

100 formed on the shaft. This roller is disposed in the channel guide 25 and cooperates with the rollers 70 in maintaining the door unit in proper movable relation along the track.

The second trolley 53 (Figs. 1 and 6) is located immediately above the junction of the door units 36 and 37, the latter of which are spaced along their adjacent edges. A vertical post 102 is disposed between these adjacent edges. This post which is somewhat similar to the post 80 is bolted rigidly as indicated at 103 to the lower mid portion of the yoke plate 78 of the second or central trolley 53 and is thus suspended from the latter.

Upper stud shafts 104 having lower heads 105 are rigidly mounted by screw-threading or otherwise in spaced relation in the plate 78 of the second or central trolley 53, and they have bearing relation respectively with blocks 106, the latter of which are rigidly secured by means of screws 109 in the frame members 40 between the flanges 45. These blocks are located at the upper inner corners of the door units 36 and 37 and the construction for mounting them corresponds substantially to that described above in connection with the hinging of the door unit 35.

A lower bar 110 is also rigidly fastened to the post by means of a screw 112 which is vertically threaded into the lower end of the post. This bar extends horizontally beyond opposite sides of the post and underlies the plate 78 for the purpose of receiving vertical stud shafts 114 which extend rotatably into blocks 115, set between the lower flanges 49 of the channel frames 41 of the door units 36 and 37. These blocks are held in place rigidly by means of screws 116 passing through the flanges 49. The stud shafts 114 have intermediate screw-threaded portions rigidly mounted in oppositely extending end portions of the bar 110 and are provided with integral lower heads 119 which support rollers 120 in the same manner as the stud shaft 92 supports the roller 98 and for the same purpose of guiding the door structure in the lower channel guide 25.

From this description it will be apparent that the yoke plate 78, post 102 and bar 110 constitute a unitary support for the adjacent door units and all of these are suspended primarily from the trolley 53. Linear spacing of the upper rollers 70 and like spacing of the lower rollers 120 is such that this unitary support is maintained in predetermined relationship and held against turning about a vertical axis while carrying the hinge connections 104 and 114 for pivotal action of the door units 36 and 37 about vertical axes 55 adjacent their opposing edges.

The third or inner end trolley 54 (Fig. 10) is constructed in substantially the same manner as those previously described with the exception that one horizontal end portion of the yoke plate 78 is omitted. Therefore, reference characters employed in defining corresponding elements of the trolleys 52 and 53 are applied in the same manner to the trolley 54. In this arrangement an upright support 130 for the opposed marginal portions of the door units 38 and 39 is sectional and includes upright post sections 131 and 132 which are joined by a so-called piano hinge 134 along one side of the post for pivotal action about a vertical axis. The hinge 134 is secured to the sections 131 and 132 by means of bolts 133 passing therethrough.

The yoke plate 78 of the trolley 54 is provided with an integral downwardly-extending arm 135 which is rigidly mounted in the upper end of the post section 131 by means of fasteners 136, such

as bolts or screws. The upwardly-extending flanges 45 of the door unit 38 receives between them a block 138 in which a vertical stud shaft 140 is mounted. The block 138 is anchored by means of screws 141 passing through the block and flanges. The upper end of the stud shaft is threaded into the yoke plate 78 and the lower end thereof is provided with a head 142 to prevent displacement of the block therefrom.

A lower bar 145 at the lower portion of the door unit is formed with an angular portion 146 rigidly mounted in the post section 131 by means of screws 148. A stud shaft 150 has an intermediate portion screw-threaded into the bar 145 in vertical and axial alignment with the stud shaft 140, and its upper end extends in bearing relation into a block 151 that is rigidly mounted between the lower flanges 49 of the door frame by means of screws 152 passing through the block and flanges. These stud shafts 140 and 150 constitute hinging members for the door unit 38.

An upper plate 154 is formed with an angular arm 156 that is rigidly mounted by means of screws 158 in the upper post section 132 and receives a stud shaft 160 vertically screw-threaded 25 therein. The lower portion of this shaft has a bearing connection in a block 161 that is mounted rigidly between the upper flanges 45 of the door unit 39 by means of screws 162 passing through the flanges and block. A lower head portion 164 on this stud shaft prevents the latter from being displaced from the block.

A lower portion of the door unit 39 is provided with a block 165 rigidly mounted between the lower flanges 49 thereof by means of screws 167 passing through the block and flanges to receive rigidly a vertical stud shaft 170 which can be more firmly anchored by means of a set-screw 171 also passing through one of the flanges 49.

The lower end of the shaft 170 extends downwardly into a horizontal casing 172 which contains conventional spring controlled hinging mechanism. Gusset plate structure 174 forms a connection between the casing and post section 132 and is rigidly secured thereto by means of screws 175. The shafts 160 and 170 are vertical and axially aligned and the door unit 39 is swingable thereabout while the post sections 131-132 remain stationary. In order to maintain these post sections in rigidly assembled relation when the door structure is in its extended position, bolts 176 (Fig. 4) are mounted therein to secure them rigidly together, while also maintaining the casing 172 in parallel alignment with the lower channel guide 25 immediately above the latter.

Bodily swingable posts 180 and 181 are disposed between the trolleys 52 and 53 and between the trolleys 53 and 54 respectively. Since the posts 180 and 181 are the same in structure and connections to the pairs of door units 35-36 and 37-38, respectively, the same description of their mountings suffices for both. Upper and lower bars 182 bolted, as indicated at 184, transversely upon upper and lower portions of each of the posts 180 and 181 receive pairs of upper and lower stud shafts 185 and 186 that constitute hinges for the edge portions of the adjacent door units 35-36 and the adjacent door units 37-38. Upper and lower pairs of blocks 190 and 191 are mounted rigidly between upper and lower flanges 45 and 49, respectively, by means of screws 192 to form bearing members for receiving the stud shafts 185 and 186 in the articulated connections between the door units and posts.

It will be observed that the posts 180 and 181

are adapted to swing outwardly when the door units are folded and that the vertical hinging axes are adjacent their marginal portions. That is, substantially the entire body of each door unit is swingable away from the vertical plane of the track 50.

In maintaining the door units in extended position as shown in Figures 1 and 3 the units of each door structure are held in aligned relation along their upper portions by means of a rail 194 (Fig. 8) which is hinged, as indicated at 195, to the overhead track structure and by means of bolts 196 which extend through these rails and are screw-threaded into openings 198 (Fig. 11) in the swingable posts 180 and 181. A resilient tube 200 of rubber, or the like, is mounted, as indicated at 201, upon a flange 202 of the rail and is pressed against the upper marginal portions of the door units in response to the fastening of the bolts 196. After the door units have been folded the rail 194 can be swung upwardly until a spring 204 mounted thereon snaps over the edge of one of the track flanges 50. This spring is secured, as indicated at 205, upon the outer portion of the rail and is sufficiently strong to hold the rail releasably in the position indicated.

Likewise, when the door units are extended, bolts 206 can be secured through the flange or thicker portion 31 of the hinged cover rail 29 and threaded into the lower portions of the posts 180 and 181 to anchor the lower portions of the door structure to the deck. In order to fold the door units, the bolts 196 and 206 are removed and the rails 29 and 194 are swung to one side. After the door units have been folded the rail 29 can be closed over the channel guide 25 substantially flush with the surface of the deck as indicated in Fig. 9. If desired, the rail 29 can be secured in its flush relation to the deck surface by means of suitable demountable fasteners 207, such as screws, which can be applied as shown in Fig. 9.

In order to provide a sealing connection between the vertical edges of the door units and the several upright posts and supports (Fig. 4), channel members 210 of plastic, rubber, or the like, are mounted in grooves 212 formed in these members and the channel members are held in place by means of screws 214. The outer edges of the channel members fit closely against the edges of the door units in sealing relation. It will be observed that the edges of the door units are rounded so as to have vertical edges all points of which are equidistant from the vertical axes of the adjacent door hinges. Thus the yieldable channel 212 members fit uniformly against the edges of the door units.

In connection with the folding of the door units, including the hinging movement of the central or entrance unit 39 about the piano hinge 134, these units can be folded and moved to the position indicated in full lines in Fig. 2. Each deck house 34 includes a compartment 215 into which the tracks and channel guides extend. A door 216 of the compartment has a vertical hinge 219 supported upon the ship superstructure and can be swung to the position indicated in broken lines.

An upper auxiliary track section 220 forms in effect a continuation of the primary overhead track 50, and a lower channel guide section 221 is likewise a continuation of the channel guide 25. The guide section 221 (Fig. 13) is rigidly mounted upon a channel arm 223 by welding,

or the like, as indicated at 224. Both of these sections 220 and 221 are rigidly secured to an upright support 225 by means of upper and lower gusset plates 226 and 227.

As shown in Fig. 14, the upper end of the post 225 has a plug 230 welded therein, as indicated at 231, and has an upright integral shaft section 232 upon which race rings 234 are mounted to receive roller bearings 235. The inner portion of the race ring structure is held in place by means of a nut 236 on an upper shouldered end portion of the shaft section.

A sleeve 240 surrounds the bearing elements, the outer portion of which is firmly secured thereon by means of a cap 241 threaded into the sleeve and anchoring the outer race ring against a shoulder 245 of the sleeve. Horizontal flanges 246 on the sleeve receive vertical bolts 247 which are adjustably mounted by means of pairs of nuts 249 and 250 secured upon structural members 251 carried by the ship superstructure and on the flanges 246, respectively. It will be observed that the race-way 252 of the bearing structure is curved so as to provide for slight angular movement of support 225 while the bearings carry the load of the support in thrust relation.

The lower portion of the support 225 has a plug 260 rigidly mounted therein by means of welding, as indicated at 261. This plug has an axial recess 262 for receiving a roller bearing structure 264 that is vertically and axially aligned with the upper bearings 234-235. A vertical shaft section 265 is rigidly mounted in a bracket 267 that is bolted as indicated at 268 to the ship deck. The bearing structure 264 is mounted upon this shaft section in such manner that the support 225 is held in a substantially vertical position and is prevented from moving laterally; such support is suspended from the upper bearings 234-235.

After each door structure has been folded and moved to a position adjacent its deck-house the door 216 is opened and the folded group of units is rolled on the trolleys from the main track 50 to the track section 220 aligned therewith. The rollers at the lower portion of the door units pass to the channel guide section 221, which is likewise aligned with the channel guide 25. This action results in a complete transfer of the door structures to the support 225 which is then swung about a vertical axis in a counterclockwise direction (Fig. 2) to a position inside the compartment 215. Then the door 216 can be closed until the folding door structure is again to be extended and placed in operative position between the deck houses in the position shown in Figs. 1 and 3. In performing this operation the support 225 is swung in a clockwise direction until the track section 220 and guide section 221 are aligned with the track 50 and guide channel 25, respectively. The door units can then be extended and fastened in place in the manner indicated above and as shown in Figs. 1 and 3.

Although only one form of the invention has been shown and described in detail, it will be apparent to those skilled in the art that the invention is not so limited, but that various changes can be made therein within the spirit of the invention and within the scope of the appended claims.

We claim:

1. A folding door structure comprising a plurality of upright doors, track means having connections with the doors for guiding them horizontally while maintaining said doors in an up-

right position, hinges connecting adjacent doors and carrying them for folding movements on vertical axes, one of said doors having an additional pivotal support movable with the door structure along the track means and supporting said door for opening and closing action independently of said hinges.

2. In a folding door structure, a series of door units having means connecting adjacent units in articulated foldable relation on substantially vertical axes, each unit including a glass panel, track means for guiding the units in movements from a position of extended aligned relation to a position of folded relation, a track section alignable with said track means for receiving the series of units thereon, an upright support carrying said track section pivotally on a vertical axis for swinging the track section with the folded units thereon away from its aligned relation with said track means.

3. In a door structure, a door supporting framework, master track means, said framework including upright supporting means carried by said track means for travel thereon, auxiliary track means alignable in juxtaposition with the master track means for receiving the door supporting framework from the master track means, supporting means carrying the auxiliary track means on a vertical axis to swing said auxiliary track means with the framework thereon to and from a position of alignment with said master track means.

4. In a door structure, a door supporting framework, master track means, said framework including upright supporting means carried by said track means for travel thereon, a door hinged upon the supporting means, means for releasably anchoring the door supporting framework on said track means, a compartment disposed adjacent said track means and receiving one extremity thereof whereby the supporting framework with the door thereon is movable as a unit upon the track means into the compartment.

5. In a door structure, a door supporting framework including upright supporting means, a door hinged upon the supporting means on a vertical axis, a compartment for confining the door supporting framework therein, a master track means extending to the compartment, means for riding the framework on said master track means to the compartment, auxiliary track means in said compartment alignable in juxtaposition with the master track means to receive said framework with the door thereon, and means for supporting said auxiliary track means on a vertical axis for swinging the door supporting framework away from the master track means into the compartment.

6. In a door structure for traversing an area of floor, a door supporting framework, primary overhead track means, said framework including upright supporting means carried by said track means for travel thereon, auxiliary track means alignable in juxtaposition with the primary track means for receiving the door supporting framework from the primary track means, supporting means carrying the auxiliary track means on a vertical axis to swing said auxiliary track means with the framework thereon away from a position of alignment with said primary track means, a channel guide member parallel to the primary track means for guiding the lower extremity of the framework along the floor, a cover plate movable on the channel guide to a

position substantially flush with the surface of the floor when the supporting frame is on the auxiliary track means and having means thereon engageable with said framework to anchor the latter in a predetermined position.

7. In a folding door structure, a series of door units, upright supporting means disposed between adjacent door units and carrying the latter pivotally on vertical axes, said upright means including sealing members engaging the edges of the door units in yieldable relation when the door units are disposed in aligned relation, track means for supporting the door units in movements from a position of extended relation to a position of folded relation, said track means extending beyond the normal operative position of the folding door structure and the latter being movable as a folded assembly upon said extension beyond its normal operative position.

8. In a folding door structure, a series of doors having means connecting adjacent doors in articulated relation on substantially vertical axes, track means for supporting the doors in movements from a position of extended relation to a position of folded relation, said track means having an extension beyond the normal operative position of the folding door structure and the latter being movable as a folded assembly upon said extension beyond its normal operative position, a cover rail hinged lengthwise along one side of the track means and swingable to and from a position of covering relation thereto after the doors have been folded, yieldable sealing means disposed longitudinally between the cover rail and the adjacent door structure, and anchoring means engageable with the cover rail and door structure for holding the doors rigidly in extended relation and for clamping the sealing means between the rail and door structure.

9. In a folding door structure, a series of doors having means connecting adjacent doors in articulated relation on substantially vertical axes, track means for supporting the doors in movements from a position of extended relation to a position of folded relation, said track means having an extension beyond the normal operative position of the folding door structure and the latter being movable as a folded assembly upon said extension beyond its normal operative position, a cover rail hinged lengthwise along one side of the track means and swingable into covering relation thereto after the doors have been folded, and means for releasably holding the cover rail in covering relation to said track means.

10. In a folding door structure, a series of doors having means connecting adjacent doors in artic-

ulated relation on substantially vertical axes, track means for supporting the doors in movements from a position of extended relation to a position of folded relation, said track means having an extension beyond the normal operative position of the folding door structure and the latter being movable as a folded assembly upon said extension beyond its normal operative position, a cover rail hinged lengthwise along the side of the track means and swingable into covering relation thereto after the doors have been folded, and means for releasably holding the cover rail in covering relation to said track means, said cover rail also being swingable to one side of the track means, and means demountably engageable with the cover rail and with the series of doors to hold the latter rigidly in extended relation.

11. In a folding door structure, a series of doors having means connecting adjacent doors in articulated relation on substantially vertical axes, upper and lower track means for guiding upper and lower extremities of the doors in movements from a position of extended relation to a position of folded relation, said track means having extensions beyond the normal operative position of the folding door structure and the latter being movable as a folded assembly upon said extensions beyond its normal operative position, cover rails hinged lengthwise along one side of the upper and lower track means and swingable into covering relation thereto after the doors have been folded, and means for releasably holding at least one of the cover rails in covering relation to its track means.

12. In a folding door structure, a series of doors having means connecting adjacent doors in articulated relation on substantially vertical axes, upper and lower track means for guiding and supporting the doors in movements from a position of extended relation to a position of folded relation, said track means having an extension beyond the normal operative position of the folding door structure and the latter being movable as a folded assembly upon said extension beyond its normal operative position, a cover rail hinged lengthwise along one side of the upper track means and swingable into covering relation thereto after the doors have been folded, and means for releasably holding the cover rail in covering relation upon said track means, said cover rail being swingable to one side of the track means, and means demountably engageable with the cover rail and the upper portions of doors to hold the latter rigidly in extended relation.

ROBERT A. MILLER.
CARROLL HOWARD.
